TABLE TOP STRUCTURE AND METHOD OF
MANUFACTUREJohn W. Beiger, Ludington, Mich., assignor to
The Carrom Company, Ludington, Mich.Application September 12, 1932
Serial No. 632,691

10 Claims. (Cl. 45—31)

This invention relates to improvements in table top structures.

As heretofore constructed, where the flexible cover has been tucked into a retaining groove there has always been a space at the outer side of the groove that was not filled and subject to receive an accumulation of dust or debris and exposing a narrow unfinished strip.

The objects of this invention are:

10 First, to provide a table top with a flexible cover in which this space is entirely closed and a tight joint formed of such perfect fit that no considerable accumulation of debris of any kind is possible and the finish of the joint is complete.

15 Second, to provide such a structure of extra strength, particularly where light weight table top panels are made use of.

Third, to provide an improved corner construction for such flexible table top structures.

20 Further objects pertaining to details will appear from the detailed description to follow. Preferred embodiments of my invention are illustrated in the accompanying drawing, in which:

Fig. 1 is a plan view of a table top embodying 25 the features of my invention.

Fig. 2 is an enlarged detail transverse sectional view on line 2—2 of Fig. 1, showing the detail of construction in process of manufacture where a comparatively light table top panel is 30 made use of.

Fig. 3 is a still further enlargement showing 35 how the retainer strip is expanded to securely clamp the flexible top covering of the structure such as seen in Fig. 2, the dotted line indicating the dimension of the compressed retainer strip before it is expanded.

Fig. 4 is an enlarged detail plan view of the 40 corner structure seen in Fig. 1 in process of manufacture before the fabric covering has been applied.

Fig. 5 is an enlarged detail sectional view on 45 line 5—5 of Figs. 1 and 4 showing the details of the structure at that point with the covering applied and the retainer strip expanded into place and clamping the edge of the flexible covering near the corner.

Fig. 6 is an enlarged detail sectional view similar to Fig. 3 where a comparatively thick table 50 top panel is shown, a simple rabbet in the outer frame is provided to receive the top panel and retainer strip, and a dotted line indicates the dimension of the compressed retainer strip before it is expanded.

1 is the table top panel which may be of wood, 55 plywood, press board, sheet metal or any suitable

material. 2 is a frame, preferably having mitered corners, and 3 is the flexible covering of any suitable material, such as leather, canvas, leathertette, or paper. The top panel 1 is disposed in a rabbet recess on the inner side of the frame 60 and is preferably retained by nails 4, although the same may be glued in place or be otherwise secured. It may be retained merely by the clamping of the covering by the retainer strip, although the greater security of nails or glue is 65 preferred. Where the panel is thin, as seen in Figs. 2, 3 and 5, I cut a groove 5 at the outer side of the rabbet in the frame, thus forming a recess 6 around the panel and within the frame. In this space and recess I put a retainer strip 7 of 70 compressed wood, basswood preferred, to which I preferably apply a thin layer of wet glue 8 on all sides. This is done preferably by injecting the wet glue from an oil can after the retainer strip has been put in place. I then roll the edge of the 75 covering 3 into the space outside the retainer strip 7 and between the said strip and the frame. This rolling is done by the usual method and frequently results in a small up-fold of the material at the bottom edge, although the up-fold is 80 not a necessity.

The strip 7, which I use most successfully, is made of basswood about three-sixteenths of an inch thick, to which I apply heavy hydraulic pressure of about three thousand pounds to the 85 square inch, reducing the same to about three thirty-seconds of an inch. When the dry retainer strip is in place, there is ample room for the rolling in of the edge of the flexible cover. The moist glue penetrates the compressed wood, 90 causing it to expand and swell to its original thickness or frequently slightly more, which entirely fills the groove, compressing and clamping the edge of the flexible covering, as seen in Figs. 3, 5 and 6. This completely closes the joint and 95 clamps the edge of the flexible cover.

I have described the retainer strip as of basswood which lends itself especially well, but most any wood will yield to heavy pressure. This is especially true of soft woods and the pressure 100 may be applied in any way to the dry wood, which upsets its fibers and forces it into compact relation. The wood must be practically dry or the fibers will not remain upset but will be resilient and open up on the release of the press. 105

I have referred to hydraulic pressure because that is really the most convenient way of doing this work in a woodworking plant where presses are made use of for veneer and the like. The pressure can be applied by any sort of means 110

and compression rollers will do the work very well. I prefer the hydraulic press on account of its convenience and power. It is not necessary to use glue. If the strip is moistened by 5 water from an oil can or the like it will expand the wood. Wet glue is preferred as it makes a glue joint besides.

It will be seen from what has been described that the corner of the flexible covering will not 10 be so effectively supported as the sides unless special provision is made. I consequently provide at each corner a piece of thin angle metal 9 of about thirty gauge. This is a small oblong rectangular piece or strip folded about the corner.

15 The fabric is rolled into the space outside of the metal between the metal and the frame. The fabric is preferably trimmed at this point so that but a single layer of the fabric is forced down into the space at the corners.

20 When the retainer strips expand they force the metal-corner strip tightly into the corner, stretching the flexible cover and making a completely closed corner by the metal extending sharply into the angle. The fabric is thus stretched in all 25 directions to exactly cover this right angle corner, making a completely closed joint. The structure will be very good without this special corner, but this completes the job, and makes the joint tight all the way around.

20 In Fig. 6 I show the form that my invention will take where a comparatively heavy top panel is made use of. There a simple rabbet is cut in the frame and the space for the retainer strip and flexible top fold is formed by the space 35 between the panel and the frame, there being no extension of the recess down into the frame into a groove.

The form shown in Figs. 1, 2, 3 and 5 is with 30 the very light panel. The form shown in Fig. 40 6 is the usual form of substantial construction of table top.

I have not shown the legs or table frame because my improved top is adapted to any sort of 35 table construction. It is especially well adapted to folding tables because it is very compact. However, it serves the purpose very well for any table where it is desired to secure a flexible top covering in place.

I have described the structure particularly in 36 tables to which it is especially well adapted. The structure is capable of a great variety of uses. The covering for chair backs or bottoms, or the chair back or bottom itself can be secured in place by this means by simply cutting a proper 40 groove in the frame. Where it is desired to provide covered panels in any wall construction, the covering may be retained by this means. A flexible covering may be retained over a panel or in any framework by this means very effectively 45 whether there is a panel supported under the covering or not.

The compressed retainer strip may be introduced in any way. It might be secured to the edge of the panel and then dampened when the 50 edge of the flexible cover is rolled in.

Having thus described my invention, what I claim as new and desire to secure by Letters Patent is:

1. In a table top structure, a table top frame 55 having a rabbeted groove to receive the top panel, a table top panel having its edges disposed in said groove and secured thereto in spaced relation to the frame forming a groove recess between the edges of said panel and frame, a retainer strip disposed in said groove, and a flexible

top covering over the said top and retainer strip and clamped between the retainer strip and frame, and an angle metal corner strip embracing the ends of said retainer strips at the corner and embraced within the said flexible top covering at the corner.

2. A table top structure having a frame with a groove therein at each side, a flexible covering the edge of which extends into said grooves, a retainer strip in the said grooves clamping the edge of said covering, and an angle metal corner strip embracing the ends of said retainer strips at the corner and embraced within the said flexible top covering at the corner.

3. The method of manufacturing table top structures which consists in providing the table top with a groove, providing a retainer strip of compressed wood in the said groove, introducing wet glue around the said retainer strip, disposing a flexible covering over the same, forcing the edge of the flexible covering into the space by the side of the retainer strip, and permitting the retainer strip to expand and clamp and glue the covering in place.

4. The method of manufacturing table top structures which consists in providing the table top with a groove, providing a retainer strip of compressed wood in the said groove moistening said retainer strip, forcing the edge of the flexible covering into the space by the side of the retainer strip, and permitting the retainer strip to expand and clamp the covering in place.

5. The method of manufacturing table top structures which consists in providing the table top with a groove, compressing a retainer strip of wood, introducing the same in said groove, introducing wet glue around the said retainer strip, disposing a flexible covering over the same, forcing the edge of the flexible covering into the space by the side of the retainer strip, and permitting the retainer strip to expand and clamp and glue the covering in place.

6. The method of manufacturing table top structures which consists in providing the table top with a groove, compressing a retainer strip of wood, introducing the same in said groove, disposing a flexible covering over the same, moistening said retainer strip, forcing the edge of the flexible covering into the space by the side of the retainer strip, and permitting the retainer strip to expand and clamp the covering in place.

7. A method of manufacture comprising the process of retaining a flexible cover, consisting in forming a groove in the framework, introducing a compressed wood retainer strip, moistening the same to expand it, and forcing the edge of the flexible covering between the said strip and the side of the groove.

8. A method of manufacture comprising the process of retaining a flexible cover, consisting in forming a groove in the framework, compressing a retainer strip of wood, introducing the same in said groove, moistening the same to expand it and forcing the edge of the flexible covering between the said strip and the side of the groove.

9. In a table top structure, a table top frame having a rabbeted groove to receive the top panel, a table top panel having its edges disposed in said groove in spaced relation to the frame and forming a groove recess between the edges of the said panel and frame, a retainer strip in said groove comprising an expanded strip of compressed wood, a part at least of which has been compressed so far within its original dimensions

and then expanded as to be under compressive forces of its expansion, and a flexible cover disposed over said panel and said retainer strip and having its edges clamped between said retainer strip and said frame, whereby said cover is stretched over said panel and said retainer strip by the compressive forces of said retainer strip.

5 10. In a furniture structure, a portion to be covered, a groove bordering said portion, a retainer strip in said groove comprising an ex-

panded strip of compressed wood, a part at least of which has been compressed so far within its original dimensions and then expanded as to be under compressive forces of its expansion, and a flexible cover disposed over said panel and said retainer strip and having its edges clamped between said retainer strip and said frame whereby said cover is stretched over said panel and said retainer strip by the compressive forces of said retainer strip.
